UNITED STATES PATENT OFFICE

1,960,840

APPARATUS FOR AND METHOD OF REMOVING DISTORTIONS FROM PRINTING PLATES

Richard M. Dugdale, Dedham, Mass., assignor to
Farrington Manufacturing Company, Boston,
Mass., a corporation of Massachusetts

Application July 17, 1931, Serial No. 551,433

3 Claims. (Cl. 153—48)

This invention relates to a method of and apparatus for straightening and reinforcing printing plates such, for example, as the type shown in my United States Patent No. 1,801,593, 5 granted April 21, 1931, which plates are used in conjunction with printing devices of the type shown in my United States Patent No. 1,801,592, granted April 21, 1931.

These plates, provided with embossed characters, are usually made of soft, thin metal and as they are usually carried on the person often become bent or distorted. The slightest distortion interferes with the printing operation and results either in non-uniform printing or an incomplete reproduction of the characters. Consequently damaged plates have to be discarded and new ones substituted.

Among the objects of my invention are to provide a simple and efficient method and apparatus 20 adapted to straighten and remove distortions from such printing plates without injuring the embossed characters thereon, and preferably also to impart to the face of the plate a convex curvature which provides a reinforcement and compensates for the tendency of the central portion 25 of the plate to sag or yield during the printing operation.

One embodiment of my invention, chosen for the purpose of illustration, is shown in the accompanying drawing, wherein:

Fig. 1 is a side elevation of the apparatus;

Fig. 2 is a section on the line 2—2 of Fig. 1 with the printing plate removed;

Fig. 3 is a section on the line 3—3 of Fig. 2;

Fig. 4 is a bottom view of one form of printing plate;

Fig. 5 is an enlarged section taken on the line 5—5 of Fig. 4; and

Fig. 6 is a section taken on the line 6—6 of Fig. 4.

The printing plate 1 usually employed in conjunction with printing devices of the aforesaid type preferably is stamped from sheet metal and shaped to provide a raised flat central portion or 45 top 2 and marginal flanges 3 spaced below the top by integral shoulders bordering a bottom recess 4, the opposite longitudinal flanges having inturned wings 5. The plate, as shown in Fig. 4, is preferably rectangular in form, although other 50 shapes may be selected according to the construction of the printing device in which a plate is to be inserted. Embossed characters 6 are stamped on the top 2 to furnish the name and address of a customer or such other data as may 55 be desirable, and when the plate is to be used

in a printing device of the aforesaid type, the characters may be arranged in non-reversed order. A thin sheet of cardboard 7 fits within the recess 4 and is retained therein by means of the inturned wings 5 and a tongue 8 struck from 60 one of the flanges 3. A more complete description of this type plate is set forth in my United States Patent No. 1,801,593, granted April 21, 1931.

The illustrated machine includes a frame 10 65 having an overhanging portion 11 in which a plunger or stem 12 is slidably mounted. A handle or lever 13 is pivotally secured to the overhanging portion 11 and is provided with a cam 14 which engages a plate 15 secured to the upper 70 end of the plunger 12. A spring 16 mounted in recess 17 engages the under side of plate 15 and normally holds the plunger in retracted position, as shown in Fig. 1.

The lower end of the plunger is provided with a 75 pressure head 18 having a convex surface, as shown in Figs. 2 and 3. A die 19 secured to the frame by a machine screw 19' preferably comprises a bed portion having a plurality of spaced longitudinally extending arcuate ribs 20 and longitudinally extending curved shoulders 21 which together define a concave surface of slightly less curvature than that of the head 16. The sides of the die are provided with flanges 22 which are in-turned at one end, as indicated at 22^a, to hold the 80 printing plate in fixed position and to prevent longitudinal movement away from the open end.

The printing plate to be straightened and/or reinforced is inserted in the die, face downward, so that the ribs 20 engage the face of the plate 90 between the rows of embossed characters and the shoulders 21 engage the marginal portions of its face, as shown in Fig. 1. When thus positioned the handle 13 is swung downwardly into the position shown by the dot and dash lines of Fig. 1, 95 thereby squeezing and clamping the plate between the die and the head, the latter engaging the back of the plate intermediate its marginal flanges 3 and inturned wings 5.

It will be noted that due to the cam action the 100 pressure is progressively applied to the plate and is maintained for the requisite time, in contradistinction to an instantaneous application such as would result from a sudden impact. This is particularly advantageous in that the ribbed portion of the die does not score or otherwise injure 105 the face of the plate.

The plate emerges from the apparatus free 110 from distortions and with a convex curvature both longitudinally and transversely, as shown in

Figs. 5 and 6. In the curved configuration thus imparted to the plate its material is disposed in position better to withstand distortion both in use and in handling than is a similar flat plate; such 5 reinforcement of the plate is obtained without adding material thereto. The convex curvature is particularly desirable in that it resists the usual tendency of the central portion of a plate to sag or yield during the printing operation, thus 10 ensuring a clear reproduction of the characters in the center of the plate as well as those around the margin.

It will of course be understood that the utility 15 of this apparatus is not confined to straightening and reinforcing damaged or distorted printing plates, but it may also be used to provide a convex curvature to new plates after the embossing operation, thereby reinforcing the same and ensuring 20 a clear and uniform reproduction of its printing characters.

While I have shown and described one desirable embodiment of my invention, I wish it understood that various changes in shape, proportion and arrangement of parts as well as the substitution of 25 equivalent elements for those herein shown and described may be made without departing from the spirit and scope of the invention as set forth in the appended claims.

I claim:

30 1. Apparatus for removing distortions from and imparting a reinforcing curvature to a printing plate of the class described having embossed characters thereon, comprising a die adapted to receive and hold in fixed position the printing plate, 35 said die having a concave surface provided with a

plurality of recesses arranged to receive the embossed characters on said plate while affording points of contact with the face of said plate intermediate some of its characters, a plunger having a head provided with a convex curvature and engageable with the opposite face of said plate, and means for actuating said plunger to clamp said plate between the die and head. 80

2. Apparatus for removing distortions from and imparting a reinforcing curvature to a printing plate of the class described having rows of embossed characters, comprising a die having a plurality of longitudinally extending curved ribs defining a longitudinally and transversely concave contacting surface, said die being adapted to receive and hold the printing plate with said ribs engaging the face of said plate between the rows of characters, a plunger having a head provided with a convex surface engageable with the opposite face of said plate, and means for actuating said plunger to clamp said plate between the die and head. 85

3. The method of removing distortions from and providing a reinforcement to a printing plate of the class described having embossed characters 90 thereon, which comprises squeezing the printing plate between opposed pressure members at points intermediate its embossed characters, and simultaneously imparting to the embossed surface of said plate a convex curvature sufficient to 100 compensate for the tendency of its central portion to sag when subjected to the printing operation. 105
